US00D573933S

(12) **United States Design Patent**
Young

(10) **Patent No.:** **US D573,933 S**
(45) **Date of Patent:** **** Jul. 29, 2008**

(54) **AUTOMOTIVE WHEEL**

(76) Inventor: **Philip B. Young**, 18400 E. Gale Ave.,
Industry, CA (US) 91748

(**) Term: **14 Years**

(21) Appl. No.: **29/293,310**

(22) Filed: **Nov. 16, 2007**

(51) **LOC (8) Cl.** **12-16**

(52) **U.S. Cl.** **D12/209**

(58) **Field of Classification Search** **D12/204-213;**
301/37.101, 64.101, 65, 64.201

See application file for complete search history.

Primary Examiner—Stacia Cadmus

(57) **CLAIM**

The ornamental design for an automotive wheel, as shown and described.

DESCRIPTION

FIG. 1 is a perspective view of an automotive wheel showing my new design; and,

FIG. 2 is a front elevational view of an automotive wheel showing the design herein described.

The broken lines showing the environment are for illustrative purposes only, and form no part of the claimed design.
